UNITED STATES PATENT OFFICE.

WALLACE G. GINDER, OF ST. JOSEPH, MISSOURI.

DESIGN FOR A LOCKET OR SIMILAR ARTICLE.

No. 38,980.

Specification for Design.

Patented Jan. 7, 1908.

Application filed November 25, 1907. Serial No. 403,833. Term of patent 7 years.

To all whom it may concern:

Be it known that I, WALLACE G. GINDER, a citizen of the United States, residing at St. Joseph, in the county of Buchanan and State of Missouri, have invented a new, original, and ornamental Design for a Locket or Similar Article, reference being had to the accompanying drawing, forming a part thereof.

The figure is a plan view of a locket case showing my new design.

I claim:

The ornamental design for a locket, or similar article, substantially as shown.

WALLACE G. GINDER.

Witnesses:

JAS. E. SPITZMESSER,
DENNIS O. SPITZMESSER.
